Primary Examiner — Martie K Holtje(74) *Attorney, Agent, or Firm* — Mark S. Leonardo; Brown Rudnick LLP(57) **CLAIM**

The ornamental design for a watch case and dial, as shown and described.

DESCRIPTION

FIG. 1 is a front perspective view of a watch case and dial showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof; and,

FIG. 7 is a top plan view thereof.

The structural features depicted with broken lines in FIG. 3 have been shown for the purpose of illustrating portions of the watch case and dial that form no part of the claimed design.
